UNITED STATES PATENT OFFICE.

SEBERON J. M. COX, OF BRISTOW, OKLAHOMA.

SPIRIT-LEVEL.

1,233,756.

Specification of Letters Patent.

Patented July 17, 1917.

Application filed June 18, 1916. Serial No. 104,587.

To all whom it may concern:

Be it known that I, SEBERON J. M. Cox, a citizen of the United States, residing at Bristow, in the county of Creek, State of 5 Oklahoma, have invented certain new and useful Improvements in Spirit-Levels; and I do hereby declare the following to be a full, clear, and exact description of the invention, such as will enable others skilled in 10 the art to which it appertains to make and use the same.

This invention relates to spirit levels and has special reference to a spirit level of improved character arranged to act both 15 as a level and clinometer, the device being arranged to indicate all angles from zero at the horizontal, to ninety degrees at the perpendicular.

One principal object of the invention is 20 to provide an improved and simplified construction for devices of this character.

A second important object of the invention is to provide means of improved character whereby the level bulb will be held in 25 position to be exposed from both sides of the level, the bulb being of greater arcuate length than three-quarters of a circle and being graduated throughout.

A third important object of the invention 30 is to provide means for holding the bulb in position which can be released to permit adjustment of the bulb so that the zero point is at the correct position.

With the above and other objects in view, 35 as will be hereinafter apparent the invention consists in general of certain novel details of construction and combinations of parts hereinafter fully described, illustrated in the accompanying drawings, and specifically claimed.

In the accompanying drawings, like characters of reference indicate like parts in the several views; and

Figure 1 is a side elevation of a level constructed in accordance with this invention;

Fig. 2 is a section on the line 2—2 of Fig. 1,

Fig. 3 is a detail view of the bulb or tube removed from the level.

Fig. 4 is a detail view of the stock, with all of the parts removed.

In the embodiment of the invention herein illustrated there has been disclosed a stock of the ordinary rectangular form, the body of this stock being indicated at 10. This stock is provided with oppositely dis-

posed recesses 11 which are preferably beveled so as to afford better opportunity for the observation of the level tube as well as to provide for better lighting of the same. 60 By reason of this construction there is provided between the two recesses a web 12 which has formed therein an annular opening 13 wherein is seated an arcuate level tube 14 provided on opposite sides with degree graduations as indicated at 15. This tube, and consequently the slots or openings 13 have lengths greater than 135 degrees, and the tube is closed by the usual plug 15' and cement 16.

The tube has its sides extending slightly beyond the faces of the web 12 and on each side of this web there is provided a cover plate 17 having an arcuate opening 18 therein opposite the tube. The edges of this opening press lightly against the tube as seen in Fig. 2, and, if desired, may be beveled to fit such tube and prevent too great pressure. These two cover plates 17 are held together by means of a bolt 19 provided with a butterfly nut 20 which is seated wholly in one of the recesses 11. The usual washers 21 are provided between the head of the bolt and adjacent plate and the butterfly nut 20 and the adjacent plate 17. One of the plates 17 is preferably secured fixedly to the stock 10 by means of suitable screws 22.

In assembling the device, the fixed plate is put into position. The bubble tube 14 is 90 then placed in the recess and the other plate 17 put in position. The bolt is then passed through the central openings of said plates and the web 12 and screwed up tight. The tube 14 is moved around the recess until 95 the bubble is exactly at zero when the stock is placed on a horizontal surface. Then when the plates are tightened together the tube can not readily move and any surface upon which the stock is placed will have its angular variation from the horizontal indicated by the graduation on the tube opposite the center of the bubble. It is to be observed that this graduation may be readily observed because of the fact that light passes freely from one side to the other of the tube through the openings 18 so that the graduations on the tube can be seen by means of the transmitted light.

It will be obvious that in case the tube 110 becomes displaced or broken it may be replaced in position by loosening the nut 20,

and if broken may be replaced by a new tube by simply removing one of the cover plates 17.

There has thus been provided a simple 5 and efficient device of the kind described and for the purpose specified.

It is obvious that many minor changes 10 may be made in the form and construction of the invention without departing from the material principles thereof. It is not therefore desired to confine the invention to the exact form herein shown and described but it is wished to include all such as properly come within the scope claimed.

15 Having thus described the invention, what is claimed as new, is:

A level comprising a stock having an arcuate opening therethrough and having circular recesses concentric to the opening,

and provided with rabbets at their inner 20 ends whereby to form a web centrally of the thickness of the stock, an arcuate level tube mounted in the opening and having a circular length greater than 135° , a pair of plates seated in said rabbets each provided 25 with an arcuate slot wherein one side of the tube is seated, a bolt extending through the plates centrally thereof, and a nut on the bolt to lock the plates and web of the stock together, the tube having graduations 30 thereon.

In testimony whereof, I affix my signature, in the presence of two witnesses.

SEBERON J. M. COX.
